UNITED STATES PATENT OFFICE

133,581

DESIGN FOR AN INSERT MEMBER FOR JEWELRY BOX

Robert Tomchin, Brooklyn, N. Y.

Application February 5, 1942, Serial No. 105,649

Term of patent 7 years

To all whom it may concern:

Be it known that I, Robert Tomchin, a citizen of the United States, residing at Brooklyn, in the county of Kings and State of New York, have invented a new, original, and ornamental Design for an Insert Member for Jewelry Box, of which the following is a specification, reference being had to the accompanying drawing, forming part thereof.

Fig. 1 is a front elevational view of an insert member for jewelry box showing my new design.

Fig. 2 is a rear elevational view thereof.

Fig. 3 is a side edge view as seen from the right of Fig. 1.

I claim:

The ornamental design for an insert member for jewelry box, as shown.

ROBERT TOMCHIN.
